(57) **CLAIM**

I claim the ornamental design for a support for computer terminals and computer keyboards, as shown and described.

DESCRIPTION

FIG. 1 is a rear elevation view of the support for computer terminals and computer keyboards showing my new design; FIG. 2 is a left side elevation view thereof; FIG. 3 is a right side elevation view thereof; FIG. 4 is a front elevation view thereof; FIG. 5 is a top plan view thereof; and, FIG. 6 is a top left perspective view thereof. The dot-dash and evenly spaced broken lines immediately adjacent to the shaded areas depict the bounds of the claimed design, while all other broken lines are directed to environment. The broken lines form no part of the claimed design.
